No. 897,816.

PATENTED SEPT. 1, 1908.

V. E. CAMPBELL.
AUTOMATIC GAS CUT-OFF.
APPLICATION FILED OCT. 15, 1906.

UNITED STATES PATENT OFFICE.

VICTOR E. CAMPBELL, OF PORTLAND, OREGON, ASSIGNOR TO CAMPBELL'S AUTOMATIC SAFETY GAS BURNER COMPANY, OF PORTLAND, OREGON.

AUTOMATIC GAS CUT-OFF.

No. 897,816.

Specification of Letters Patent.

Patented Sept. 1, 1908.

Application filed October 15, 1906. Serial No. 339,027.

To all whom it may concern:

Be it known that I, VICTOR E. CAMPBELL, a citizen of the United States, residing at Portland, in the county of Multnomah and 5 State of Oregon, have invented a new and useful Automatic Gas Cut-Off, of which the following is a specification.

This invention relates to devices of that class employed for automatically cutting off 10 the flow of gas through a gas burner in case the flame is accidentally extinguished, or in the case of failure to ignite the gas after the latter has been turned on. In devices of this class where a thermostatic element has been used 15 for the purpose of controlling a gas cock turning mechanism it has been usual to so arrange the thermostat as to hold the cock closing mechanism from movement during the time the gas is lighted, and the thermostat is expanded. It has been found that where the 20 heated thermostat is under constant strain during all the time the gas is lighted, there is considerable danger of moving the parts to inoperative position or effecting a permanent 25 lengthening of the thermostatic element, so that the latter cannot always be relied upon.

In carrying out the present invention, one of the principal objects is to so arrange and connect the thermostat that the latter will 30 be subjected to strain only when cool, and when in this condition there is less likelihood of permanent injury than where the strain is exerted on the heated thermostat.

A further object of the invention is to provide 35 a device of this character in which the pressure exerted on the controlling devices shall be uniform at all times without regard to slight variations in temperature of the heated thermostat.

40 A still further object of the invention is to provide a device of this character in which the thermostatic element is heated by an auxiliary flame at one side of and below the tip of the burner, thus improving the appearance of the device and rendering it much more compact than where the thermostat is extended into or above the main flame.

With these and other objects in view, as will more fully hereinafter appear, the invention 45 consists in certain novel features of construction and arrangement of parts, herein-after fully described, illustrated in the accompanying drawings, and particularly pointed out in the appended claims, it being understood 50 that various changes in the form, pro-

portions, size and minor details of the structure may be made without departing from the spirit or sacrificing any of the advantages of the invention.

In the accompanying drawings:—Figure 1 60 is a side elevation of an automatic gas cut off constructed in accordance with the invention, parts being broken away in order to more clearly illustrate the construction. Fig. 2 is an edge view of the same, the casing and other parts of the structure being shown in section. Fig. 3 is a vertical section of the device on the line 3—3 of Fig. 2. Fig. 4 is an elevation looking from the side opposite that shown in Fig. 1. Fig. 5 is an 70 inverted plan view of a portion of the device drawn to an enlarged scale.

Similar numerals of reference are employed to indicate corresponding parts throughout the several figures of the drawings.

The working parts of the cut off are supported principally by a vertically disposed tube 10 that preferably is of rectangular form in cross section, and is provided with a 80 bore 11 through which the gas passes. The lower end of the tube is provided with a threaded socket 12 for the reception of a nipple on the gas supply pipe, and the upper end of the tube carries a nipple 13 on which may 85 be screwed a gas burner 14 of any desired type, the device being intended for use in connection with the ordinary flat flame burners or any other type of burners such, for instance as the Bunsen, Welsbach, or other incandescent mantles or burners. Arranged within this tube 10 is a tapered plug valve 16 which is provided at one end with a handle 17 or like member to be used in moving the valve port 18 into and out of alignment with 95 the main gas passage 11.

Arranged in the wall of the tube 10 is a small gas passage 20 which terminates at the valve chamber, and the plug valve carries an auxiliary port 21 which is moved into communication with this passage when the gas is turned on, so that a small quantity of gas may flow outward through a burner orifice 22 arranged inside the main burner, in much the same fashion as a pilot light, this auxiliary burner being used for heating the thermostat element.

Secured to the opposite sides of the tube 10 are plates 25 and 26 that preferably are in the form of circular disks, and these disks 110

have bearing openings for the arbors of a train of gears 27, the first gear 28 of this train being mounted loosely on the projecting end of the plug valve, and this gear is 5 mutilated, forming two shoulders 29 which serve by engagement with a stop pin 30 to limit the turning movement of the plug valve when the latter is automatically restored to its closed position. The mutilated 10 gear engages with a pinion 31, the arbor of which carries a ratchet wheel 32 which engages with a pawl 33 on one of the gears of the train 27, so that said ratchet wheel may be turned from the mutilated gear without 15 transmitting rotative movement to the gear train.

Secured to the hub of the mutilated gear 28 is the inner end of a spiral spring 36, the outer end of said spring being secured to a 20 bracket 37 that is carried by the plate 25, and when the mutilated gear is turned, the spring is placed under stress, and if allowed to operate, will transmit movement to all of the gears of the train, and will further serve 25 to restore the valve to its closed position. The stem of the valve carries a projecting pin 39 which is arranged to engage a pin 40 that is carried by the hub of the mutilated gear, and each time the operating handle 17 30 is turned for the purpose of moving the valve to open position, the pin 39 will engage the pin 40, and the mutilated gear will be turned, and the spring placed under stress. The mutilated gear and the spring will be held in 35 the position to which they are adjusted by the means hereinafter described, while the valve is left free in order to cut off the flow of gas to the burner.

The final arbor or shaft 43 of the gear train 40 is extended through the plate 26 and carries a brake wheel 44 that is adapted to be engaged by a brake lever 45 that is pivoted on a pin 46. The brake lever carries a spring 47 which bears at one end against a pin 48, 45 said spring tending at all times to force the lever 45 into engagement with the brake wheel, and when these springs are engaged, the gear train will be held from movement under the influence of the spring. If, however, the brake lever is moved away from the 50 wheel, and the spring is under stress, the mutilated gear will be turned, and this movement will be transmitted through the pin 40 and the pin 39 to the valve, the latter being turned to closed position and cutting off the flow of gas to the burner.

Arranged to one side of the tube 10 is a 55 small block 50 from which extends a tube 51 formed of readily expandible material, the upper end of the tube being closed. The upper portion of the tube is arranged immediately adjacent the auxiliary burner 22, and when heated will expand, and when the burner is extinguished will contract. Arranged with- 60 in this tube and connected to the upper

end thereof, is a rod 53, formed of material having a lower coefficient of expansion than that of the tube. The lower end of the rod is bent outwardly, forming an arm 56 that is arranged over an arm 57 that is pivoted at 70 one end to a bracket 58 depending from the block 50. The free end of the arm 57 extends through a slot 59 in the plate 26, and is arranged to engage the brake lever 45 at a point close to the pivot pin 46 of the latter. 75

It will be seen that when the flame is lighted and the thermostat is heated, the rod 53 will be pulled up and the arm 56 will not be pressed against the arm 57, so that so long as the thermostat is heated, the spring 47 is 80 free to act to force the brake lever 45 into engagement with the brake wheel 44 and then hold the train of gears from movement. If the gas is accidentally extinguished at the burner, or if the gas is not ignited after being 85 turned on, the thermostat will contract, or will not be expanded, and the arm 56 will then press forcibly against the arm 57 and the latter will move the lever 45 from engagement with the brake wheel 44, so that the train of gears is free to operate and turn the valve to 90 its closed position. From this it will be seen that during the time the thermostat is heated there is no strain on the thermostat and there is but little danger of the latter becoming inoperative. When the thermostat is not heated, it is better able to stand the strain without danger of injury, and it is during this time that the thermostatic element is at 95 work and holds the brake lever in inoperative position. The apparatus as a whole is preferably inclosed within a suitable casing 100 60 which may be of globular or any other form and may be made ornamental or plain as desired. 105

It will be noted that the thermostat is disposed entirely below the illuminating burner and that the pilot is interposed between the burner 14 and the thermostat so that the flame from the pilot will at all times contact with the thermostat and there is no danger of it being blown away therefrom. Attention is also called to the fact that the valve 110 16 simultaneously opens and closes the passages to the main burner and to the pilot. 115

Where the thermostat is used in connection with burners of the Welsbach or other type, it is preferred to make the thermostat long enough to extend up into the globe in such position as to be exposed to the heat 120 from the main burner. In such cases the pilot flame or auxiliary burner is, of course, dispensed with.

I claim:—

1. The combination with a tube having a 125 burner at one end, and an auxiliary burner disposed below and adjacent the first mentioned burner and disposed to receive gas from the tube; of a plug valve for shutting off the supply of gas to the burners, a brake 130

wheel, means operated by the movement of the valve for rotating the brake wheel, a spring pressed brake member disposed to automatically bear against and hold the brake wheel against movement, an arm pivoted adjacent and disposed to bear downward upon the brake member, and a thermostat disposed adjacent the auxiliary burner and adapted to be heated by a flame therefrom to release the arm and the brake member, said brake member being normally held by the arm and thermostat out of contact with the brake wheel.

2. The combination with a burner; of a valve for cutting off the flow of gas to the burner, a brake wheel, a spring pressed lever disposed to automatically contact with the brake wheel to hold it against rotation, a pivoted arm bearing upon the lever, a thermostat disposed when cool to bear upon the arm to hold the lever out of contact with the brake wheel, said thermostat being disposed to be heated by a flame from the burner, and mechanism disposed to be actuated upon the cooling of the thermostat and the release of the brake wheel for operating the valve to cut off the gas supply to the main burner.

3. The combination with a main illuminating burner and a gas cock; of a closing spring for said cock which is placed under stress on opening movement of the cock, brake means for preventing operative movement of the spring and the closing of the cock while the gas is burning, a pilot burner, and a thermo-

stat element supported solely at its base and terminating short of the main burner, said element and all parts connected thereto being disposed entirely outside of the field of light of the main burner, said thermostat element being adapted to be heated by a flame from the pilot burner and designed when cooled by the extinguishing of said flame to shift said brake means into position to permit closing of the cock.

4. The combination with a main illuminating burner and a pilot burner therebelow; of a single gas cock for simultaneously turning on or shutting off gas for the two burners, a closing spring for said cock which is placed under stress on opening movement of the cock, brake means for preventing operative movement of the spring and the closing of the cock while the gas is burning, and a thermostat element to be heated by a flame from the pilot burner and designed when cooled by the extinguishing of said flame to shift said brake means into position to permit closing of the cock, said thermostat and all parts connected thereto being disposed outside of the field of light of the main burner.

In testimony that I claim the foregoing as my own, I have hereto affixed my signature in the presence of two witnesses.

VICTOR E. CAMPBELL.
